DOOR ENGINE CONTROL

Filed Feb. 28, 1920

UNITED STATES PATENT OFFICE

LEE P. HYNES, OF ALBANY, NEW YORK, ASSIGNOR, BY MESNE ASSIGNMENTS, TO CONSOLIDATED CAR-HEATING COMPANY, INC., OF ALBANY, NEW YORK, A CORPORATION OF NEW YORK

DOOR-ENGINE CONTROL

Application filed February 28, 1920. Serial No. 362,162.

In the accompanying drawing:—

Figure 1 is a diagrammatic view illustrating the door motor without the controls. Figure 2 is a diagrammatic view showing the controls for the motor of Figure 1. Figures 1 and 2 are so disposed with respect to each other, that their cooperation is apparent. Figures 3, 4 and 5 are detail sectional views illustrating the valve lifting and holding mechanism.

My invention relates to the power operation of doors, such as car doors on railway trains. It involves an arrangement for enabling the door to make its full run by only 15 a momentary pressure on the button, also means for avoiding excess pressure in the cylinder in the event of the door sticking fast, as by reason of ice or snow, or its being blocked or obstructed by any other cause.

Referring to the drawing, the figure shows 20 diagrammatically a door engine such as shown in full in Letters Patent No. 1,479,386 of January 1, 1924. The diagrammatic illustration permits an easier understanding of its 25 mode of operation being free from the details of physical structure which I have claimed in my application aforesaid.

In the drawing A and B represent the two 30 opposed, single-acting cylinders of a door-engine wherein travel two pistons C and D connected by a rigid rod E. The rod E, by means well known to the art, will connect with and operate the door when the rod moves to right or left under air pressure applied to the cylinders B and A. Each cylinder has a pair of control valves, each pair 35 having a common valve stem. The valves for A are shown at G and K; those for B at F and H. By these valves each cylinder will be opened to the atmosphere or to the pressure-supply alternately. The fluid pressure-supply is shown at 10. Thus if the rod carrying valves F and H is lifted up, F will be 40 opened and H closed; then the pressure-air from pipe 10 will flow to cylinder B through 20. If, however, the rod be forced down by the spring at its upper end F will be closed and H opened; then the pressure-air will be cut off from B which will now be open to 45 atmosphere through H. In the same way the

pair of valves G and K serve to connect cylinder A to the atmosphere when their valve rod is pushed down by the spring, and to the source of pressure in pipe 10 when the rod is lifted up against the force of said spring. 55 When either admission valve F or G is open, the air will flow from the pressure source via pipe 10 to pipe 20, to adjuster valve 14 (it is stopped by check valve 18 from entering the cylinder at port 42) and thence 60 through the inwardly-opening check valve 17 to the head of the cylinder. The branch from 14 through adjuster valve 16 into the cylinder is so restricted, as, compared with the route through 17, that only a very little air will enter the cylinder by that branch. 65 When, however, one of the exhaust valves H or K is open (F or G being then closed) the air in the cylinder will at first flow out freely through port 42 and outwardly-opening 70 check valve 18 to pipe 20, to the atmosphere. When, however, the piston (D or C) in its backward travel passes over the port 42 there is no outlet from the cylinder save by the restricted passage through valve 16. 75 Hence the remainder of the backward travel of the piston is retarded or cushioned by the slow escape of the trapped air through 16, 80 from whence it flows through valve 14 and pipe 20 to the atmosphere through H or K. 85 We may assume that cylinder A acts to close the door, cylinder B to open it. The closing movement thus involves air pressure in A to the right of its piston C and a movement of both pistons, together with rod E, from 90 right to left as indicated by the arrow and the illustrated position of the pistons. To obtain the desired air pressure in the cylinder A, it is requisite that the valves G and K be lifted so that the air will flow from the pipe 10, past the valve G to the cylinder A by the route which has been described down, thereby opening cylinder B to atmosphere at H and shutting it off at F from the source of supply. The foregoing explains in outline 95 the mode of operation of the engine in said Letters Patent No. 1,479,386.

Any desired means may be employed for lifting one or the other of the two sets of valves to either close or open the door. It is 100

preferred however, to utilize the valve lifting and control means disclosed in Letters Patent 1,479,386, dated January 1, 1924. The apparatus of this patent is provided with an electromagnetic device whereby the momentary pressure of an electric button will cause the lifting of the desired set of valves and the retention of it in lifted position until the engine has made its full stroke. At the 10 end of its stroke the engine will itself restore the said retention means to neutral position so as to allow the valves to drop by the force of their spring, the admission valve being thereby closed, the exhaust valve open. The 15 engine will of course then remain at rest until the opposite set of valves is lifted when, in the same way it will make its reverse stroke and at the end knock out the retention means and allow the lifted set of valves to drop. A 20 part of the apparatus disclosed in said patent is diagrammatically illustrated in the drawing, as follows, P represents a bar arranged under the two valve rods so as to be pulled to the right by a solenoid 50 and to the left by 25 a solenoid 60. This bar P is dead, that is, it has no retracting spring and remains in whichever position it has been pulled by one solenoid or the other, or in its intermediate position to which it is moved by the engine 30 itself. In the bar P is a recess in which is seated a sliding latch block or retention dog P¹, the recess being somewhat longer than the block, which can thereby slide back and forth in the recess to a limited extent. At 35 each end of the recess is a cam or incline—they are marked p p²—on the upper edge of the bar P, by means of which one or the other of the two valve rods may be lifted, when the bar is moved to the left or right. The 40 continued movement of the bar shoves the block P¹ under the lifted rod to retain it in its lifted position. Thus a momentary closure of the circuit of one of the solenoids by a push button will lift one of the valve rods and latch it in its raised position by the 45 block. When in response to such lifting of a valve rod, the engine makes its stroke, the bar will be automatically shifted back to its intermediate position between the two solenoids at the end of the stroke, and also knock out the latching block which has retained the valve rod in its lifted position thereby restoring the valves to neutral position. For such automatic action any mechanical means 50 may be employed. I have indicated such means by lugs R and S on the outer face of pistons D and C which, at the end of the stroke, will engage lever T and move it to its upright position and the lever T, by means 55 of a slot and pin connection will restore bar P to its intermediate or neutral position, when both sets of valves are down, the retaining block having been knocked from under the lifted valve rod and caused it to suddenly drop. The controlling push-button for 60

solenoid 50 is shown at 1; when it is closed, current from battery 2 flows to the solenoid, by way of wire 3 and the button and thence by the route identified by the letters a, a, etc. In a similar manner button 40 controls solenoid 60, the current route from the button to the solenoid being identified by the letters b, b, etc. Thus by a momentary push on button 1 or button 40, the door will be either closed or opened by the engine since the valves which produced that movement are held up by the block P¹ till the movement has been completed. 70 75

For avoiding an accumulation of excessive pressure in the cylinder in the event of the door sticking or being blocked I provide a relief valve 26 in the pipe 44 which leads to that valve from the outlet duct of side port 42 in the wall of the door-closing cylinder A. By connecting the relief-valve to the cylinder at this point, the port 42 will serve two functions, viz, the conduction of the exhaust air flowing to the exhaust valve K and the conduction of pressure to the relief-valve. It also prevents the relief-valve from acting at the beginning of the stroke when a higher pressure is desired for initiating the door movement. When the relief-valve 26 acts, by a predetermined degree of pressure in the cylinder A, its spring is compressed and air passes by the valve, part of it going out through a restricted port 41 and the remainder going to the cylinder 28 which acts, in the way I will now describe, to reverse the engine so that cylinder A in which the excess pressure had occurred will be opened to the atmosphere and the pressure shifted to door-opening cylinder B. The aforesaid cylinder 28 contains a spring-pressed piston 29 which operates an electric contact-block 30 which operates with stationary contact pins 31, 32, 33. The block 30 normally bears on pin 31, and as its moves leftward it engages first the pin 32 and then the pin 33. When the relief-valve 26 acts to admit air to cylinder 28, the piston 29 moves block 30 till it bridges pins 31 and 32. Then the current from battery 2 flows by the route d, d, etc., to pin 32 and from pin 31 by the route f, f, etc., to the point 70 where it connects with the line a, a, etc., leading to solenoid 50. That energizes said solenoid 50 but causes no new effect because that solenoid has already pulled bar P to the right to inaugurate the closing and the bar still stands in that position. When, however, the block 30 moves still farther to the left, breaking connection with pin 31 and bridging pins 32 and 33 then several things happen. Solenoid 50 is de-energized and lets go of bar P while solenoid 60 (the current from battery 2 and pin 32 now going to pin 33 and via the route g, g, etc., to relay 37 and thence via route b, b, etc., to solenoid 60 and ground) pulls bar P to the left, thereby reversing the engine and the door starts to 130 110 115 120 125

back away from the obstruction. It does not, however, move far, because the reversal of the engine has removed the pressure from cylinder A and relief-valve 26. That allows piston 29 to draw back the block 30 so that it no longer bridges pins 32 and 33, but pins 32 and 31, which, as heretofore explained, energizes solenoid 50 and de-energizes solenoid 60. Thereupon the engine is reversed back again to its door-closing condition and the door starts once more on its closing run. If in the meanwhile the movement of the resistance to the door has been overcome or removed, the door proceeds to close; if not, the accumulated excess pressure again works the relief-valve 26 and the actions just described are repeated. By this means the door, if it encounters undue resistance keeps moving back and forth a short distance feeling out, so to speak, the resistance ahead of it. If it finds the resistance removed or reduced it proceeds to close the door; if not it can keep on repeating its tentative advances without producing excessive pressure in the closing cylinder. In order that the doorman may not unwittingly prevent the backward movement of the door, I provide the aforesaid relay magnet 37 which is in the circuit from pin 33 to the solenoid 60. This relay magnet, when energized acts to open at contacts 4 the circuit route *a*, *a*, etc., from the battery and push-button 1 to the solenoid 50 and to hold it open so long as the solenoid 60 is working. Hence the doorman cannot, by pushing button 1, excite the solenoid 50 to set the engine into its door-closing condition.

What I claim as new and desire to secure by Letters Patent is:

1. A fluid pressure engine comprising a cylinder and a piston, a valve actuator for setting said valves to open the admission and to close the exhaust ports, an electromagnetic device for operating said actuator, a switch for momentarily energizing said electromagnetic device, a retainer positioned to engage said valves, and an operating connection for moving said retainer to disengage it from said valves at the end of the stroke of the piston.

2. The combination with the admission valve of a fluid pressure engine, of an operating spring therefor set to close said valve, a valve actuator for opening said valve in opposition to the tension of said spring, an electromagnetic device for operating said actuator, a switch for momentarily energizing said electromagnetic device, a retainer mounted to engage and hold the valve in closed position, and an operating connection with the engine for tripping said retainer at the end of its stroke so as to release said valve.

3. The combination with the admission valve of a fluid pressure engine, of an exhaust valve operating simultaneously therewith, an operating spring normally acting to close the

admission valve and to open the exhaust valve, a valve actuator for operating said valves against the tension of said spring, an electromagnetic device for operating said actuator, a switch for momentarily energizing said electromagnetic device, a retainer mounted to engage said valves so as to hold them in working position, and an operating connection to a moving part of the engine for shifting said retainer so as to release the valves therefrom at the end of the piston stroke whereupon the valves will be moved by said spring.

4. The combination with the admission valve of a fluid pressure engine, of a spring tending to hold said valve closed, a valve actuator having a retaining device for engaging said valve so as to hold it in open position in opposition to the tension of said spring, an electromagnetic device for moving said actuator to open position and so connected that said actuator tends to remain in the position to which it is moved, a switch for momentarily energizing said electromagnetic device, and an operating connection to a moving part of the engine for moving said retaining device so that said valve will be freed for operation by said spring at the end of the stroke of the piston.

5. The combination with a double acting engine, of a separate set of valves for each end, springs tending to close the admission valves, a valve actuator having retaining means for engaging and holding said valves against the force of their respective springs, electromagnetic devices for moving said actuator so as to open one admission valve at a time and to simultaneously close the associated exhaust valves, two switches for momentarily energizing said devices, and operating means worked by the engine to move said retaining means so as to free the valves at the end of each stroke of the engine.

6. The combination with a double acting engine of separate admission valves for its respective ends, independent electro-magnetic devices for opening the respective valves, separate switch contacts corresponding to the respective valves for energizing said electro-magnetic devices, energizing contacts also controlling the respective admission valve, and pressure means dependent upon the amount of load imposed upon the engine when in action for controlling said contacts.

7. The combination with a double-acting engine of separate admission valves for its respective ends, independent electromagnetic devices for opening the respective valves, separate switch contacts corresponding to the respective valves for energizing said electro-magnetic devices, retaining means for said valves governed by the engine travel, and energizing contacts also corresponding to the respective admission valves and dependent on the amount of load im-

posed upon the engine in action for releasing said retaining means.

8. The combination with a double-acting engine of separate admission valves for its respective ends, electromagnetic operating devices for said valves, separate switch contacts corresponding to the respective valves for energizing said devices, retaining means for the valves controlled by the engine travel, and a vibrating contact dependent on the amount of load imposed upon the engine for opening said valves alternately.

9. The combination with a double-acting fluid pressure engine of starting contacts for initiating electrically the action of the engine, means for shifting the engine control from said contacts to the engine itself, and a vibrating reverser responding in its action to the amount of load imposed upon the engine and independent of the said control by the engine itself of its own movement.

10. The combination with a double-acting fluid-pressure engine, of separate starting contacts for initiating electrically the respective forward and backward strokes of the engine, means for shifting the engine control from each starting contact to the engine itself comprising a retainer dependent on the engine stroke, and a vibrating reverser responding to the amount of load imposed upon the engine and independent of the completion of the engine stroke.

11. The combination with a double acting fluid pressure engine of starting circuits for initiating electrically the action of the engine in either direction, reversing contacts, means co-operating with said contacts controlling said circuits, control means for said reversing contacts actuated by back pressure in the engine due to amount of load imposed thereupon, and automatic stopping means operated by the engine at the end of its stroke.

12. The combination with a double acting fluid pressure engine, electrical starting means, automatic stopping means, and a reverser responding to back pressure created by any increased load encountered by the engine in action, and independent of said electrical starting means.

13. The combination with a double acting, fluid pressure engine of an electrical controller therefor, a reverser responding to the backing up of fluid pressure incident to an increased load imposed upon the engine while in action and an electrical disabling means for said controller.

14. The combination with a double acting, fluid pressure engine of an electrical controller therefor, and an electrical reverser responding to the backing up of fluid pressure incident to an increase of load encountered by the engine in action.

15. The combination with a double-acting, fluid-pressure engine, of an electrical controller therefor, an electrical reverser re-

sponding to the backing up of fluid pressure incident to any increase in load encountered by the engine in action, and a circuit-breaker governed by the reverser for disabling the said controller.

16. The combination with a double-acting, fluid-pressure engine, of an electrical controller therefor comprising separate starter contacts, a valve shifter operated by both of said contacts, and reversing contacts for said shifter controlled by the backing up of fluid pressure incident to resistance encountered by the engine in action.

17. The combination with a double-acting, fluid-pressure engine, of separate admission valves for its respective ends, springs tending to close said valves, a shifter for opening said valves alternately, separate starting contacts controlling said shifter, retaining means for the valves and supplementary contacts for said shifter operated automatically by the engine according to any variations in the load which it encounters in action.

18. The combination with a double-acting, fluid-pressure engine, of an electrical starter therefor, supplementary contacts for reversing the engine and a piston subject to cylinder pressure controlling said contacts.

19. The combination with a double-acting, fluid-pressure engine, having both a free exhaust port and pressure-cushioning means, of a valve for closing the outlet from said port in the pressure period, a piston and cylinder communicating with said port, means associated with said piston for reversing the engine, and means whereby the engine reversing means is automatically controlled by pressure against said piston when movement of the engine is obstructed.

20. The combination with a double-acting, fluid-pressure engine, of an electrical starter therefor, and an automatic reverser therefor responding to the resistance encountered by the engine in action and comprising a contact stationary with respect to the engine movement and a co-operating contact moved by a piston subject to the pressure in the engine cylinder.

21. The combination with a double-acting, fluid-pressure engine, of an electrical controller therefor, comprising a valve shifter, separate contacts for moving the shifter electrically to its respective starting positions, retaining means controlled by the termination of the engine travel, reverser contacts independent of the termination of the engine travel, and a piston for operating said reverser contacts subject to the pressure in the engine cylinder.

Signed at New York city, county and State of New York, this 26th day of February, 1920.

LEE P. HYNES.
